UNITED STATES PATENT OFFICE.

ELMER E. HAUER, OF SPRINGFIELD, OHIO, ASSIGNOR TO THE LAGONDA MANUFACTURING COMPANY, OF SPRINGFIELD, OHIO, A CORPORATION OF OHIO.

ROTARY MOTOR.

1,102,743.

Specification of Letters Patent.

Patented July 7, 1914.

Application filed December 18, 1911. Serial No. 666,517.

To all whom it may concern:

Be it known that I, ELMER E. HAUER, a citizen of the United States, residing at Springfield, in the county of Clark and State of Ohio, have invented certain new and useful Improvements in Rotary Motors, of which the following is a specification, reference being had therein to the accompanying drawings.

10 My invention relates to rotary motors and more particularly to motors of this type adapted to drive boiler tube cleaners, although it may be used for other purposes.

15 The object of my invention is to provide an improved motor simple, strong and durable that can be easily assembled and readily taken apart.

20 A further object of my invention is to provide improved means adapted to relieve the friction between the stationary and rotary members and to balance the rotary member.

25 A further object is to provide improved means for lubrication and for the admission and discharge of the motive agent.

With these and other objects in view my invention consists of the constructions and combinations hereinafter described and set forth in the claims.

30 In the accompanying drawings which form a part of this specification Figure 1 is a longitudinal section of a motor embodying my invention, taken on the line A—A of Fig. 3. Figs. 2, 3 and 4 are cross-sections taken on the lines 2—2, 3—3 and 4—4 respectively of Fig. 1. Fig. 5 shows detail of spring pressed dowel-pin, Fig. 6 is a longitudinal section showing modifications and Figs. 7, 8 and 9 are cross-sections on 35 the lines 7—7, 8—8 and 9—9 respectively of Fig. 6, and Fig. 10 shows another modification.

Like numerals represent the same parts in the several views.

45 In the drawings 1 represents a motor cylinder having an outwardly projecting ring 2 forming an abutment. A two-part casing 3 having heads at its outer ends preferably formed integrally therewith extends over 50 and is screw-threaded to said cylinder with its inner ends tightened against said abutment.

55 In the present instance I have shown the motor cylinder forming a chamber of such dimensions that when the rotary member 4

is mounted therein it will contact with the walls of the chamber in two places, opposite each other, forming two oppositely disposed chambers 5 and 6 as particularly shown in Fig. 3. Piston blades 7 are seated 30 in recesses 8 of the rotary member and are adapted to move radially into the chambers 5 and 6 in a well known manner.

The rotary member I preferably form with front and rear journals integral therewith of less diameter than the body thereof as shown. A motor journal bearing member 9 is seated in one part of the casing 3 and a removable bushing 10 is preferably provided to carry the rear journal of the 70 rotary motor member; and a removable bushing 11 seated in an opening in the head of the other part of said casing is provided to carry the front journal of said rotary motor member. Said front journal portion 75 projects through said head and is screw-threaded at 12 to attach a tube cleaner or other tool to be driven.

The motive agent is admitted to the working chambers 5 and 6 through inlet 80 ports 13 which enter through the periphery of the rear journal and extend through the body of the rotary motor member with openings in the rear of the piston blades as shown. It will be seen these ports are so arranged that the transverse portions can be made by boring through the periphery of the rotary motor and its rear journal and the longitudinal section of it can be bored from the outer end of the rear journal and 90 a plug 14 employed to close the open end. The bushing 10 is provided with inlet ports 15 adapted to register with the ports 13 of the rotary motor member. Said bushing is secured to the motor bearing member 9 by 95 a key 16 and said bearing member is secured to the cylinder 1 by a dowel-pin 17 so that the ports 13 and 15 will be held in proper relation to admit the motive agent. The longitudinal section of the port 15 may 100 be bored from the end of the bushing and its transverse section through the wall thereof, its outer end being closed by the bearing member 9; and this transverse section of the inlet 15 is of greater width at 105 its inner end than it is at its outer end as particularly shown in Fig. 2. The dowel-pin 17 is spring pressed by a spring 18 into a recess 19 in the bearing member 9. Said recess is beveled at one side as particularly 110

shown in Fig. 5 so that when the rear part of the casing 3 is unscrewed from the cylinder, if the bearing member 9 should stick in the casing and turn with it, the dowel-pin, 5 being spring pressed, will give and slide out on the bevel side of the recess 19.

The front head of the casing is provided with segmental openings 20 to receive and discharge the exhaust from the ports 21 in 10 a plate 22 seated between said head and the cylinder. Said openings 20 are of greater length than the ports 21 to allow for any variation in the position of said openings and ports when the front part of the casing 15 is screwed in place against the abutment. Said plate 22 is secured by dowel-pin 23 to the cylinder so as to hold the exhaust ports 21 in proper relation to the cylinder.

Conduits 24 extending from the inlet ports 20 13 to the front end of the rotary motor member admit the motive agent to said end to balance said member; and a cross-port 25 from the working chamber is also to be used for this purpose. I preferably enlarge the 25 conduit 24 at its outer end as shown, as I have found that such pockets, even without the supply conduits 24 and 25, give a larger area of the motive agent which acts as a cushion between the end of the rotary motor 30 member and the wall of the chamber and reduces the friction.

Any suitable means may be employed for introducing a lubricant with the motive agent into the motor and I have provided 35 an opening 26 through the plate 22 into an annular chamber 27 which has a conduit 28 leading through the front head and bushing to the front bearing for the purpose of giving the lubricant in the motive agent free 40 access to said bearing. The rear head of the casing is shown with a screw-threaded opening 29 to secure the supply conduit; and a plate 30 closes the rear end of the rear bearing of the motor.

45 In Figs. 6, 7, 8 and 9 I have shown some modifications as to the admission of the motive agent and balancing the rotary motor member. In its modified form the motor journal bearing member 9^a is made shorter 50 thus providing a chamber 30 into which the bushing 10^a projects a sufficient distance to permit the port 15^a to enter and pass transversely through the wall of said bushing from said chamber. As to balancing the rotary motor member by the pressure of the motive agent, this may be accomplished by providing openings 31 through said member as shown in Fig. 10; or by providing a conduit 55 32 leading from the chamber 30 through the walls of the casing 3, the abutment 2 and plate 22 to the front end of the rotary motor member as shown in Figs. 6 to 9 inclusive. The longitudinal section of this conduit 32 can be made by boring from the inner ends 60 65 of the casing and the transverse sections by

boring through the periphery of the casing and closing the open ends by plugs 33. Where the conduit passes through the abutment 2 at 32^a it is enlarged or elongated in cross-section as particularly shown in Fig. 7 76 to allow for any variation in the position of the conduit when the two parts of the casing are screwed against the abutment.

Having thus described my invention I claim:—

1. In a rotary motor, a motor cylinder having an abutment on the outer surface thereof, a two-part casing having heads at its outer ends and screw-threaded to said cylinder with its inner ends against said abutment, and a rotary motor member having radially moving blades operative within said cylinder, said member being journaled in the respective heads of said casing, substantially as described.

2. In a rotary motor, a motor cylinder having an abutment on the outer surface thereof, a two-part casing having heads at the outer ends thereof and screw-threaded to said cylinder with its inner ends against said abutment, one of said heads having exhaust openings therethrough, a ported plate secured against rotation at one end of said cylinder and held in place by said exhaust head and a rotary motor member having radially moving blades operative within said cylinder, said member being journaled in the respective heads of said casing, substantially as described.

3. In a rotary motor, a motor cylinder having an abutment on the outer surface thereof, a two-part casing having heads at the outer ends thereof and screw-threaded to said cylinder with its inner ends against said abutment, one of said heads having a supply opening for the motive agent, a removable bearing secured against rotation at one end of said cylinder and held in place by said supply head, and a rotary motor member having radially moving blades operative within said cylinder, said member having a journal in said removable bearing, substantially as described.

4. In a rotary motor, a motor cylinder having an abutment on the outer surface thereof, a two-part casing having heads at the outer ends thereof and screw-threaded to said cylinder with its inner ends against said abutment, one of said heads having a supply opening and the other exhaust openings for the motive agent, a ported plate at one end of said cylinder and a removable journal bearing member at the other end, said plate and bearing member being secured against rotation to said cylinder and tightened and held in place by said casing, substantially as described.

5. In a rotary motor, a motor cylinder having an abutment on the outer surface thereof, a two-part casing having heads at

its outer ends and screw-threaded to said cylinder with its inner ends against said abutment, said heads having removable bearings therein, a rotary motor member 5 journaled in said bearings, one of said heads having a supply opening and the other exhaust openings for the motive agent, a ported plate secured against rotation to said cylinder and tightened and held in place by one 10 end of said casing, substantially as described.

6. In a rotary motor, a motor cylinder having an abutment on its outer surface, a two-part casing having integral heads at 15 its outer ends, the head of one part having a removable bush bearing and discharge openings for the motor, a ported plate inserted through the open end of said part and seated against said head, a motor journal bearing member having a removable bushing, said member being inserted and removable from the open end of the other part 20 of said casing, each of the parts of the casing extending over and being screw-threaded to the cylinder with its inner end 25 against said abutment to tighten and hold said plate and bearing member in place, and means to fix said plate, bearing member and cylinder in their relation to each other, substantially as described.

7. In a rotary motor, a cylinder forming a motor chamber, a two-part casing having heads at the outer ends of the respective parts with bearings seated therein, the inner ends of said bearings terminating outside of said chamber and the inner ends of the respective parts of said casing extending beyond said bearings over said cylinder and being screw-threaded thereto and a rotary motor member 35 in said chamber having journals in said bearings, substantially as described.

8. In a rotary motor, a cylinder forming a motor chamber, a two-part casing having 45 heads at the outer ends of the respective parts with bearings seated therein, the inner ends of said bearings terminating outside of said cylinder chamber, one of said bearings forming an end wall of said chamber and a wear plate forming the opposite end wall, the inner ends of the respective parts of the casing extending beyond said bearings over said cylinder and being screw-threaded thereto and a rotary motor member 50 in said chamber having journals in said bearings, substantially as described.

9. In a rotary motor, a cylinder forming a motor chamber, a two-part casing having heads at the outer ends of the respective 60 parts with bearings seated therein, the inner ends of said bearings terminating outside of said chamber, a rotary motor member in said chamber having front and rear journals of less diameter than the body thereof 65 in said bearings and a port entering through

said rear journal and opening to said chamber, one of said heads having a supply opening parallel to the axis of the motor with means to periodically register with said port, the inner ends of the respective parts 70 of said casing extending beyond said bearings over said cylinder and being screw-threaded thereto, substantially as described.

10. In a rotary motor, a motor cylinder having an abutment on the outer surface thereof, a rotary motor member in said cylinder, means to balance said member by the pressure of the motive agent, and a two-part casing screw-threaded to said cylinder against said abutment.

11. In a rotary motor, a motor cylinder having an abutment on the outer surface thereof, a two part casing screw-threaded to said cylinder against said abutment, a rotary motor member with a radially moving blade and front and rear journals of less diameter than the body thereof, said rotary motor member having an inlet port or passage entering through the periphery of the rear journal and opening in the rear of said 90 blade, a removable bearing for said rear journal having a port therethrough with which the port or passage in the rotary motor member periodically registers, and means for balancing said rotary motor member 95 by the pressure of the motive agent, substantially as described.

12. In a rotary motor, a motor cylinder, a two-part casing having integral heads at its outer ends, one of said heads having a removable bush bearing and segmental discharge openings for the motor, a ported plate secured against rotation to the front end of said cylinder seated against said head, a motor journal bearing member having a removable bushing, said member being inserted through and removable from the open end of the other part of said casing, each of the parts of the casing extending over and being screw-threaded to said cylinder.

13. In a rotary motor, a motor cylinder having a motor chamber therein with front and rear bearings and an abutment on the outer surface thereof, a rotary motor member journaled in said bearings, a two-part casing screw-threaded to said cylinder against said abutment, said casing having a lubricant passage leading from said motor chamber to said front bearing.

14. In a rotary motor, a motor cylinder and a casing therefor having a head, a motor journal bearing member seated in said head and having a recess to receive a spring pressed dowel-pin held by said cylinder, said casing being screw-threaded to said cylinder and said recess being beveled at one side to permit said pin to slide out of said recess when said casing is unscrewed from said cylinder.

15. In a rotary motor, a motor cylinder, a two-part casing having heads at the outer ends of the respective parts, the inner ends of said parts extending over said cylinder and being screw-threaded thereto, motor bearing members seated in said heads outside of said cylinder, a rotary motor member in said cylinder having journals in said bearings, means to introduce the motive agent through one of said journals to drive said motor member and means to conduct the motive agent to the respective ends of said motor to balance said member, one of said

journal bearing members having a recess to receive a spring-pressed dowel-pin held by 15 said cylinder, said recess being beveled at one side to permit said pin to slide out of said recess when said casing is unscrewed from said cylinder.

In testimony whereof I have hereunto 20 affixed my signature in the presence of two witnesses.

ELMER E. HAUER.
